(57) **CLAIM**

We claim the ornamental design for a combination saw and torch, as shown and described.

DESCRIPTION

FIG. 1 is a top, front and left side perspective view of the combination saw and torch, with the saw, illustrated in broken lines, in a folded position;

FIG. 2 is a bottom, back and right side perspective view thereof;

FIG. 3 is a left side elevational view thereof;

FIG. 4 is a right side elevational view thereof;

FIG. 5 is a front side elevational view thereof;

FIG. 6 is a back side elevational view thereof;

FIG. 7 is a top plan view thereof; and

FIG. 8 is bottom plan view thereof;

FIG. 9 is an alternative top, front and left side perspective view thereof with the saw in an unfolded position; and

FIG. 10 is a bottom, back and right side perspective view of the torch of FIG. 9.

FIG. 11 is a top, front and left side perspective view thereof, with the saw, illustrated in broken lines, in a folded position, wherein a top cover is removed to reveal the torch;

FIG. 12 is a bottom, back and right side perspective view thereof;

FIG. 13 is a left side elevational view thereof;

FIG. 14 is a right side elevational view thereof;

FIG. 15 is a front side elevational view thereof;

FIG. 16 is a back side elevational view thereof;

FIG. 17 is a top plan view thereof; and,

FIG. 18 is a bottom plan view thereof.

The broken lines shown in the drawings illustrate portions of the combination saw and torch in which the article is embodied that form no part of the claimed design.

1 Claim, 8 Drawing Sheets
